IGNITION SYSTEM FOR INTERNAL
COMBUSTION ENGINESMelville F. Peters, Beltsville, Md., and George F.
Blackburn, Washington, D. C.

Application November 20, 1940, Serial No. 366,430

19 Claims. (Cl. 123—148)

(Granted under the act of March 3, 1883, as
amended April 30, 1928; 370 O. G. 757)

This invention relates generally to electrical ignition systems for internal combustion engines, and particularly to circuits for reducing primary breaker point contact arcing in such ignition systems.

An object of our invention is to provide an improved ignition circuit for internal combustion engines in which the current flow through the primary breaker point contacts never exceeds a small value, and is only a small part of the total primary current.

Another object of our invention is to provide an improved ignition system for internal combustion engines which includes a discharge tube means to carry the greater part of the primary current.

Another object of our invention is to provide an improved ignition system for internal combustion engines in which the primary breaker point contacts make and break only a small current initiating the discharge of an electron tube means, the latter providing an interruptible path for the greater portion of the primary current.

A further object of our invention is to provide an improved ignition system for internal combustion engines which permits a reduction in the contact area of the primary breaker point contacts and in which the arcing at such contacts is reduced.

Our invention is a modification and improvement of the ignition system claimed and described in U. S. Patent No. 2,184,315, granted to us on December 26, 1939. In the system described in this patent, advantage was taken of the discharge of one primary circuit capacitor and the substantially simultaneous charge of another in the production of the secondary high voltage, and the primary circuit breaker point contacts were not opened until the current flow through them had reached zero or a low value.

However, when using the system described in the aforementioned patent in connection with certain internal combustion engines operating at very high speeds, it has been found, especially in circuits not having a low time constant, that the primary breaker point contacts are opened while there is still an appreciable current flow through them, there not being sufficient time for the capacitors to become fully charged and/or discharged before the breaker point contacts are opened at such speeds. Such results in arcing and consequent wearing away of the contacts, necessitating frequent adjustment or renewal thereof. Arcing of these contacts also occurs, but to a lesser extent, when they are closed. Ob-

viously, these contacts must have a sufficient contact area to carry the high though momentary peak discharge and charging currents of the primary capacitors.

5 Our present invention overcomes this undesirable excessive arcing at the primary breaker point contacts in installations where it occurs, by providing a parallel electron discharge tube path for the far greater part of the primary current, the 10 primary breaker point contacts carrying and breaking only the very small current for initiating the electron discharge through the tubes, and having resistors in series therewith which limit the current through the contacts to a very low 15 value.

With the above and other objects in view, our invention will be described in connection with the accompanying drawing which is an electrical and mechanical schematic diagram incorporating our 20 invention in its preferred form.

Referring to the drawing, the positive supply line 2 from a conventional engine driven generator or other direct current source of electrical energy (not shown) is connected to one terminal of 25 capacitor 3 and of a resistor 4, and is further connected to fixed breaker point contact 5 and to the anode 6 of a cold-cathode discharge tube 7. The negative supply line 8 from the same direct current source is connected to one terminal of 30 capacitor 9, to the cathode 12 of a second cold-cathode discharge tube 13, and is further connected to grids 14, 15 of tube 13 through resistors 10 and 11, respectively. Grid 15 is also connected to movable breaker point contact 16 through resistor 17. A storage capacitor 2' is preferably 35 connected across the positive supply line 2 and the negative supply line 8, but if the source has a sufficiently low internal resistance this capacitor will not be required for satisfactory operation 40 of our invention. The remaining terminals of capacitors 3, 9 and resistor 4 are connected together and are further connected to one terminal of the primary winding 18 of iron core step-up transformer or induction coil 19. The other 45 terminal of primary winding 18 is connected to fixed breaker point contact 20, to the cathode 21 of tube 7, to the anode 22 of tube 13, and is further connected to grids 23 and 24 of tube 7 through resistors 25 and 26, respectively. Grid 24 is also 50 connected to movable breaker point contact 27 through resistor 28. One terminal 29 of the secondary or high voltage winding 31 of transformer 19 is connected to ground, the other terminal 30 being connected to a conventional

type distributor (not shown) of the engine, or to a spark plug (not shown) thereof.

Breaker point contacts 5, 27 and 16, 20 are mounted on spring arms which tend to close the electrical circuits including these respective pairs of contacts. A rotatable engine-driven cam 32 operates to break the circuit at these contacts in accordance with the timing of the engine.

Secondary winding 31 is wound with many times the number of turns as primary winding 18, and is disposed in inductive relationship therewith, such that the secondary voltage will be sufficient to jump the spark gap within a cylinder of the engine. Capacitors 3, 9 are preferably, though not necessarily, of equal capacity. Resistors 10, 25 serve as biasing resistors for grids 14, 23, respectively, and as such assist in fixing the breakdown operating points of tubes 7 and 13.

In operation, assuming the engine at rest with contacts 5, 27 closed and contacts 16, 20 open, with voltage applied across capacitor 2' of polarity as indicated, capacitor 9 will be charged to substantially the terminal voltage of the source through the circuit including closed contacts 5, 27, resistors 28 and 26, and primary coil 18. Due to the presence of resistors 28, 26 in series in this circuit, the current flow through contacts 5, 27 will never exceed a small value. If now the engine be started, the rotation of cam 32 in the direction shown will first open the circuit at contacts 5, 27, and will immediately afterwards permit contacts 16, 20 to close. Capacitor 9 having previously been charged in the manner explained below, the closing of contacts 16, 20 applies a sufficiently positive voltage to grid 15 of tube 13 by means of resistors 17 and 11, to cause this tube to become conductive, a low resistance electron discharge path being formed between the anode and the cathode thereof. Capacitor 9 then discharges rapidly through the circuit including the primary coil 18 of transformer 19 and this low resistance electron path between the anode and cathode of tube 13, such discharge being accompanied by the substantially simultaneous charge of capacitor 3, also through primary coil 18 and tube 13, the charging current of capacitor 3 and the discharge current of capacitor 9 flowing through primary coil 18 in the same direction. This charging current for capacitor 3 is supplied by storage capacitor 2', if used, or from the direct potential source, and capacitor 3 is charged to substantially the terminal potential of the source. As cam 32 rotates further in the direction shown, contacts 16, 20 are opened and contacts 5, 27 are permitted to close immediately thereafter. Such imposes a sufficiently positive voltage on grid 24 of tube 7, through resistors 28 and 26, to cause this tube to become conductive, whereupon capacitor 3 immediately discharges through the circuit including the primary coil 18 of transformer 19 and the conductive electron path through tube 7, such being accompanied by the substantially simultaneous charge of capacitor 9, also through a circuit including primary coil 18 and tube 7. Here also the discharge current of capacitor 3 and the charging current of capacitor 9 flow through primary coil 18 in the same direction, capacitor 9 again being charged from capacitor 2' or the source to substantially the terminal voltage of the latter.

As cam 32 continues to rotate in the direction shown, the above described cycle is repeated.

The circuit including contacts 5, 27 and re-

sisters 28, 28 may be called the trigger circuit for tube 7, and these elements plus cam 32 may be referred to as the trigger means for this tube. Similarly, the circuit including contacts 16, 20 and resistors 11, 17 may be called the triggering circuit of tube 13, and these elements plus cam 32 may be referred to as the trigger means for tube 13.

The discharge of one capacitor and the charge of the other occurring substantially simultaneously through the primary winding 18 of transformer 19, the current surges due to these respective discharges and charges also occur practically simultaneously, resulting in a cumulative effect thereof in the production of the secondary high voltage. Advantage was also taken of this cumulative effect in the aforementioned patent, which contains a more complete exposition thereof.

Our present invention has other advantages in common with our aforementioned patented invention, one of which is that the flow of current from the source is more nearly uniform than in the case of systems employing a single capacitor, since, except for brief interruptions occurring twice each cycle, either capacitor 3 or capacitor 9 is being charged. Secondly, since the cumulative effect of the charging current surge of one capacitor and the discharge current surge of another is utilized in producing the secondary high voltage, capacitors 3, 9 may each have less capacity than would be necessary in the case of a single large capacitor. Since capacitors 3, 9 may have less capacity, their peak charging current is correspondingly less, and a smaller, lighter, less expensive source of charging current may be employed.

Our present invention preferably employs a transformer 19 having a single primary winding 18 through which the charging and discharging current of both capacitors 3, 9 flows. It is obvious that a dual primary transformer of the type used in the aforementioned patent could also be employed in our present invention, one such primary winding being connected in the circuit shown at point *a*, the other primary winding being connected at point *b*, in which case the current flow through each primary winding would always be uni-directional.

Resistor 4 is used in the circuit to insure that capacitor 9 is charged to substantially the full terminal voltage of the supply source when the ignition system is turned on, when the engine has been stopped in such position that both pairs of contacts 5, 27 and 16, 20 are open. If resistor 4 were not employed and the ignition system were turned on after the engine had been stopped for a considerable period with both sets of breaker point contacts open, the voltage of the supply source would be distributed across capacitors 3 and 9 in series. Then if an attempt were made to start the engine, the reduced voltage across either capacitor 3, 9 would not be sufficient, in some installations, to cause either tube 7, 13 to discharge. The previous charge on either condenser 3, 9 as well as that on capacitor 2', would leak off during the period while the engine was idle, in most installations.

While the use of cold-cathode discharge tubes is preferable in our present invention, it is obvious that hot cathode types could be employed with correspondingly satisfactory results. Furthermore, discharge tubes with a fewer number of elements than the tubes shown would also produce satisfactory operation. While we do not

limit ourselves to such, we have found tubes of the Strobotron type 631:P-1, manufactured by the Hygrade Sylvania Corp., to be satisfactory for use as tubes 1, 12. With tubes of the latter type employed, we have found that currents of the order of five milliamperes or less through the circuits including contacts 5, 27 and 16, 20 will provide a sufficient voltage on grids 24 and 15 to cause these tubes to become conductive, as described above.

With contacts 5, 27 and 16, 20 breaking only currents of the order mentioned above, arcing troubles at these contacts are completely eliminated. Further, since these contacts never carry currents greater than those mentioned above, their size and contact area may be reduced correspondingly.

The following specific values have been found satisfactory for use in the circuit shown. We emphasize that these are only suggested values that have produced satisfactory operation, and we do not limit ourselves to such, or even to values of the order of those listed below. In the circuit shown, capacitor 2' may have a capacity of 8 microfarads. Capacitors 3, 9, have a capacity of 2 microfarads each. Resistor 4 may have a resistance of 1 megohm; resistors 17, 28—10,000 ohms each; resistors 11, 26—100,000 ohms each; resistors 10, 25—250,000 ohms each.

It will be understood that the above description and accompanying drawing comprehend only the general and preferred embodiment of our invention and that various minor changes in detail of construction, proportion and arrangement of parts may be made within the scope of the appended claims without sacrificing any of the advantages of our invention.

The invention herein described may be manufactured and used by or for the Government of the United States for government purposes without the payment of any royalties thereon or therefor.

We claim:

1. In combination, a source of electrical energy of substantially constant potential, a first capacitor and a second capacitor electrically connected in series across said source, a step-up transformer having a primary winding and a secondary winding, a first space discharge means and a second space discharge means each having a grid, a first common circuit including said primary winding and said first discharge means for charging said first capacitor and discharging said second capacitor, a second common circuit including said primary winding and said second discharge means for discharging said first capacitor and charging said second capacitor, means including a cam actuated contact means cyclically operable to apply a sufficient voltage to said grids to cause said discharge means to become alternately conductive, a charging resistor connected across said first capacitor, and a storage capacitor connected across said source, the current flowing through said contact means being of the order of a few milliamperes, the flow of charging current from said source being substantially uninterrupted, said first capacitor being charged and said second capacitor being simultaneously discharged through said first common circuit, said first capacitor being discharged and said second capacitor being simultaneously charged through said second common circuit.

2. In combination, a source of electrical energy,

a first capacitor and a second capacitor electrically connected in series across said source, a step-up transformer having a primary winding and a secondary winding, a first space discharge means and a second space discharge means each having a grid, a first common circuit including said primary winding and said first discharge means for charging said first capacitor and discharging said second capacitor, a second common circuit including said primary winding and said second discharge means for discharging said first capacitor and charging said second capacitor, means including a cam actuated contact means cyclically operable to apply a sufficient voltage to said grids to cause said discharge means to become alternately conductive, a charging resistor connected across said first capacitor, and a storage capacitor connected across said source, the current flowing through said contact means being of a relatively low value, said first capacitor being charged and said second capacitor being simultaneously discharged through said first common circuit, said first capacitor being discharged and said second capacitor being simultaneously charged through said second common circuit.

3. In combination, a source of electrical energy, a first capacitor and a second capacitor electrically connected in series across said source, a step-up transformer having a primary winding and a secondary winding, a first space discharge means and a second space discharge means each having a grid, a first common circuit including said primary winding and said first discharge means for charging said first capacitor and discharging said second capacitor, a second common circuit including said primary winding and said second discharge means for discharging said first capacitor and charging said second capacitor, means including a cam actuated contact means cyclically operable to apply a sufficient voltage to said grids to cause said discharge means to become alternately conductive, and a charging resistor connected across said first capacitor, said first capacitor being charged and said second capacitor being simultaneously discharged through said first common circuit, said first capacitor being discharged and said second capacitor being simultaneously charged through said second common circuit.

4. In combination, a source of electrical energy, a first capacitor and a second capacitor electrically connected in series across said source, a step-up transformer having a primary winding and a secondary winding, a first space discharge means and a second space discharge means each having a grid, a first common circuit including said primary winding and said first discharge means for charging said first capacitor and discharging said second capacitor, a second common circuit including said primary winding and said second discharge means for discharging said first capacitor and charging said second capacitor, means including a cam actuated contact means cyclically operable to apply a sufficient voltage to said grids to cause said discharge means to become alternately conductive, and a charging resistor connected across said first capacitor.

5. In combination, a source of electrical energy of substantially constant potential, a first capacitor and a second capacitor electrically connected in series across said source, two space discharge means, a step-up transformer having a primary winding and a secondary winding, a

first circuit for charging said first capacitor and discharging said second capacitor including said primary winding and one said discharge means, a second circuit for discharging said first capacitor and charging said second capacitor including said primary winding and the other said discharge means, a trigger means including a cam actuated contact means cyclically operable to cause said discharge means to become alternately conductive, said first capacitor being charged and said second capacitor being simultaneously discharged through said first circuit and alternately said first capacitor being discharged and said second capacitor being simultaneously charged through said second circuit, a charging resistor connected across said first capacitor, and a storage capacitor connected across said source, the current flow through said contact means being limited to a very small value.

6. In combination, a source of electrical energy, a first capacitor and a second capacitor electrically connected in series across said source, two space discharge means, a step-up transformer having a primary winding and a secondary winding, a first circuit for charging said first capacitor and discharging said second capacitor including said primary winding and one said discharge means, a second circuit for discharging said first capacitor and charging said second capacitor including said primary winding and the other said discharge means, a trigger means including a cam actuated contact means cyclically operable to cause said discharge means to become alternately conductive, said first capacitor being charged and said second capacitor being simultaneously discharged through said first circuit and alternately said first capacitor being discharged and said second capacitor being simultaneously charged through said second circuit, and a charging resistor connected across said first capacitor, the current flow through said contact means being limited to a very small value.

7. In combination, a source of electrical energy, a first capacitor and a second capacitor electrically connected in series across said source, two space discharge means, a step-up transformer having a primary winding and a secondary winding, a first circuit for charging said first capacitor and discharging said second capacitor including said primary winding and one said discharge means, a second circuit for discharging said first capacitor and charging said second capacitor including said primary winding and the other said discharge means, a trigger means including a cam actuated contact means cyclically operable to cause said discharge means to become alternately conductive, said first capacitor being charged and said second capacitor being simultaneously discharged through said first circuit and alternately said first capacitor being discharged and said second capacitor being simultaneously charged through said second circuit, and a charging resistor connected across said first capacitor.

8. In combination, a source of electrical energy, a first capacitor and a second capacitor electrically connected in series across said source, two space discharge means, a step-up transformer having a primary winding, a first circuit for charging said first capacitor and discharging said second capacitor including said primary winding and one said discharge means, a second circuit for discharging said first capacitor and

charging said second capacitor including said primary winding and the other said discharge means, means including a cam actuated contact means cyclically operable to cause said discharge means to become alternately conductive, and a charging resistor connected across said first capacitor.

9. In combination, a source of electrical energy of substantially constant potential, two capacitors electrically connected in series across said source, a step-up transformer having a primary winding and a secondary winding, two space discharge means, trigger means including a cam actuated contact means cyclically operable to cause said discharge means to become alternately conductive, circuit means responsive to said trigger means for charging one said capacitor and simultaneously discharging the other said capacitor through said primary winding and one said discharge means, and for alternately discharging the previously charged capacitor and simultaneously charging the previously discharged capacitor through said primary winding and the other said discharge means, a charging resistor connected across one said capacitor, and a storage capacitor connected across said source, the current flowing through said trigger means being only a small proportion of the total primary current.

10. In combination, a source of electrical energy, two capacitors electrically connected in series across said source, a step-up transformer having a primary winding and a secondary winding, two space discharge means, trigger means including a cam actuated contact means cyclically operable to cause said discharge means to become alternately conductive, circuit means responsive to said trigger means for charging one said capacitor and simultaneously discharging the other said capacitor through said primary winding and one said discharge means, and for alternately discharging the previously charged capacitor and simultaneously charging the previously discharged capacitor through said primary winding and the other said discharge means, and a charging resistor connected across one said capacitor, the current flowing through said trigger means being only a small proportion of the total primary current.

11. In combination, a source of electrical energy, two capacitors electrically connected in series across said source, a step-up transformer having a primary winding and a secondary winding, two space discharge means, trigger means including a cam actuated contact means cyclically operable to cause said discharge means to become alternately conductive, circuit means responsive to said trigger means for charging one said capacitor and simultaneously discharging the other said capacitor through said primary winding and one said discharge means, and for alternately discharging the previously charged capacitor and simultaneously charging the previously discharged capacitor through said primary winding and the other said discharge means, and a charging resistor connected across one said capacitor.

12. In combination, a source of electrical energy of substantially constant potential, two capacitors electrically connected in series across said source, a step-up transformer having a primary winding and a secondary winding, two space discharge means, means including a cam actuated contact means cyclically operable to charge one said capacitor and to simultaneously

discharge the other said capacitor through said primary winding and one said discharge means, and alternately to discharge the previously charged capacitor and to simultaneously charge the previously discharged capacitor through said primary winding and the other said discharge means, a charging resistor connected across one said capacitor, and a storage capacitor connected across said source, the current flowing through said contact means being limited to a very small value.

13. In combination, a source of electrical energy, two capacitors electrically connected in series across said source, a step-up transformer having a primary winding and a secondary winding, two space discharge means, means including a cam actuated contact means cyclically operable to charge one said capacitor and to simultaneously discharge the other said capacitor through said primary winding and one said discharge means, and alternately to discharge the previously charged capacitor and to simultaneously charge the previously discharged capacitor through said primary winding and the other said discharge means, and a charging resistor connected across one said capacitor, the current flowing through said contact means being limited to a very small value.

14. In combination, a source of electrical energy, two capacitors electrically connected in series across said source, a step-up transformer having a primary winding and a secondary winding, two space discharge means, means including a cam actuated contact means cyclically operable to charge one said capacitor and to simultaneously discharge the other said capacitor through said primary winding and one said discharge means, and alternately to discharge the previously charged capacitor and to simultaneously charge the previously discharged capacitor through said primary winding and the other said discharge means, and a charging resistor connected across one said capacitor.

15. In combination, a source of electrical energy of substantially constant potential, two capacitors electrically connected in series across said source, a step-up transformer having a primary winding, a space discharge means, a trigger means including a cam actuated contact means cyclically operable to cause said discharge means to become conductive, means including said discharge means responsive to said trigger means for charging one said capacitor and simultaneously discharging the other said capacitor through said primary winding, and alternately for discharging the previously charged capacitor and charging the previously discharged capacitor through said primary winding, a charging resistor connected across one said capacitor, and a charging capacitor connected across said source.

16. In combination, a source of electrical energy, two capacitors electrically connected in series across said source, a step-up transformer

5 having a primary winding, a space discharge means, a trigger means including a cam actuated contact means cyclically operable to cause said discharge means to become conductive, means including said discharge means responsive to said trigger means for charging one said capacitor and simultaneously discharging the other said capacitor through said primary winding, and alternately for discharging the previously charged capacitor and charging the previously discharged capacitor through said primary winding, and a charging resistor connected across one said capacitor.

17. In combination, a source of electrical energy, a first capacitor and a second capacitor electrically connected in series across said source, a step-up transformer having a primary winding, a space discharge means, a triggering means for said discharge means, a charging and discharging means for said capacitors including said primary winding and said discharge means, said triggering means being cyclically operable to cause said first capacitor to become charged and said second capacitor to simultaneously become discharged through said charging and discharging means, and alternately to cause said second capacitor to become charged and said first capacitor to simultaneously become discharged through said charging and discharging means, a charging resistor connected across said first capacitor, and a storage capacitor connected across said source.

18. In combination, a source of electrical energy, a first capacitor and a second capacitor electrically connected in series across said source, a step-up transformer having a primary winding, a space discharge means, a triggering means for said discharge means, a charging and discharging means for said capacitors including said primary winding and said discharge means, said triggering means being cyclically operable to cause said first capacitor to become charged and said second capacitor to simultaneously become discharged through said charging and discharging means, and alternately to cause said second capacitor to become charged and said first capacitor to simultaneously become discharged through said charging and discharging means, and a charging resistor connected across said first capacitor.

19. In combination, a source of electrical energy, a pair of capacitors connected in series across said source, a step-up transformer having a primary winding, a space discharge device connected in parallel with each of said capacitors through the primary winding of said transformer, means for simultaneously charging one and discharging the other of the capacitors in said pair through the primary winding of the transformer but alternately through the space discharge devices, and a charging resistor connected across one said capacitor.
